BACK SUPPORTING GIRDLE

This invention relates generally to the field of women's figure control garments, and more particularly to an improved form of high waist back supporting girdle, particularly adapted for use by wearers who spend a large part of the wearing period in sitting condition.

It is among the principal objects of the present invention to provide a relatively lightweight girdle providing mild support to the lower back of the wearer, while in no way interfering with the comfort of the wearer while in a seated condition.

Another object of the invention lies in the provision of an improved back supporting garment of the class described which may include a plurality of stiffening members commencing at a portion approximately overlying the coccyx of the wearer, and extending radially outwardly and upwardly from that point to terminate in the upper edge of the garment overlying the waist of the wearer.

Yet another object of the invention lies in the provision of an improved back supporting garment adapted to provide improved gentle support to the wearer in the area beneath the rib cage on either side of the spine, without interfering with normal body movements in this area.

Still another object of the invention lies in the provision of an improved support garment which may be of relatively lightweight construction, permitting the comfortable wearing thereof in warm ambient temperatures.

A further object of the invention lies in the provision of an improved support garment, possessed of the above advantages, in which the cost of fabrication may be of a reasonably low order, directly comparable with existing prior art devices, thereby permitting consequent wide sale, distribution, and use.

A feature of the disclosed embodiment lies in the ready adaptability of the inventive structure for use either with panty type or open bottom type garments.

These objects and feature, as well as other incidental ends and advantages, will more fully appear in the progress of the following disclosure, and be pointed out in the appended claims.

In the drawing, to which reference will be made in the specification, similar reference characters have been employed to designate corresponding parts throughout the several views.

FIG. 1 is a front elevational view of an embodiment of the invention.

FIG. 2 is a rear elevational view thereof.

FIG. 3 is a front elevational view thereof, partly broken away to show detail.

FIG. 4 is an enlarged fragmentary horizontal sectional view as seen from the plane 4-4 in FIG. 1.

FIG. 5 is an enlarged fragmentary horizontal sectional view as seen from the plane 5-5 in FIG. 1.

FIG. 6 is an enlarged fragmentary horizontal sectional view as seen from the plane 6-6 in FIG. 3.

In accordance with the invention, the device, generally indicated by reference character 10, includes broadly: a left-hand lower peripheral panel 11, a right-hand lower peripheral panel 12, an outer left rear panel 13, an outer right rear panel 14, an inner left rear panel 15, an inner right rear panel 16, an upper resilient band member 17, a front panel 18, and a plurality of elongated stiffening members, generally indicated by reference character 19.

The left lower peripheral panel 11 is formed of elastic corseting material, and is bounded by a continuous lower edge 22, a front vertical edge 23, a rear vertical edge 24, bordering edges 25 and 26, and a continuous upper edge 27.

The right lower peripheral panel 12 is generally symmetrical, and is bounded by a continuous lower edge 29, a front vertical edge 30, a rear vertical edge 31, bordering edges 32 and 33, and a continuous upper edge 34.

5 The outer left rear panel 13 and inner left rear panel 15 are generally congruent, and are interconnected together to be bounded by an upper rectilinear edge 37, a vertical rear edge 38, a vertical front edge 39, and a curved lower edge 40. Similarly, the outer right rear panel 14 and inner right rear panel 16 are interconnected to be bounded by an upper rectilinear edge 43, a vertical rear edge 44, a vertical front edge 45 and a curved lower edge 46.

10 The upper resilient band member 17 is of relatively heavy elastic material, and is bounded by an upper edge 49 interconnected to the upper edges 34 and 37, and a lower relatively free edge 50. The body of the member 17 is also interconnected to the garment along the rear seam 51, and at the vertical edges of the front panel 18.

15 The front panel 18 is formed of relatively nonelastic material, and is bounded by an upper edge 53, vertical side edges 54 and 55, and lower converging edges 56 and 57. A slide fastener 58 allows for the opening of the garment along the major portion of its length, to permit convenient donning and doffing of the same by a wearer.

20 The elongated stiffening members 19 are best seen in FIGS. 2, 3 and 6, and are most conveniently five in number. As seen in FIG. 3, first, second, third, fourth and fifth members 61, 62, 63, 64 and 65, respectively, are formed of thin resilient synthetic resinous material, rather than conventional steels, and are enclosed in a felt casing portion 66 to be maintained by stitch means 68.

25 As seen in FIG. 2, the stitch means penetrates the inner and outer panels 13-15, and 14-16 and serves as a means of maintaining the same in overlying relation over a substantial area of the garment. Each of the members 61-65, inclusive terminates at the lower end thereof at closely spaced locations 69, all of which generally overlie the coccyx area of the wearer, and at upper locations 70 at the waist portion of the garment.

30 Thus, as best seen in FIGS. 2 and 3, the stiffening members clear the rear portions of the buttocks of the wearer, and allow complete flexibility of the garment in those areas which must flex upon the wearer assuming a seated position. While in such position, the supporting members add gentle support to that portion of the back of the wearer disposed below the rib cage, where the wearer is most likely to slump during extended periods in a seated posture.

35 Referring to FIGS. 1 and 5, where desired, additional stiffening means may be placed along the vertical edge 54 and adjacent the slide fastener 58, as indicated by reference character 59 to assist in maintaining the shape of the garment in the forward portion thereof.

40 I wish it to be understood that I do not consider the invention limited to the precise details of structure shown and set forth in this specification, for obvious modifications will occur to those skilled in the art to which the invention pertains.

I claim:

45 1. A back-supporting girdle comprising: a plurality of elastic panels interconnected to enclose the pelvic and lower back portions of the wearer, and a plurality of generally rectilinear stiffening members incorporated into said garment to be disposed in mutually upwardly diverging relation commencing at a point substantially overlying the coccyx of the wearer and extending radially from said point to terminate substantially at the waist portion thereof, at least one of said stiffening members overlying the spine of the wearer, said plurality of elastic panels having a continuous upper edge, and an elastic member interconnected to said panels at said upper edge.
